UNITED STATES PATENT OFFICE.

CHARLES D. YOUNG, OF ALTOONA, PENNSYLVANIA.

DAMPER FOR BOILERS.

1,172,000.

Specification of Letters Patent. Patented Feb. 15, 1916.

Application filed January 16, 1915. Serial No. 2,542.

To all whom it may concern:

Be it known that I, CHARLES D. YOUNG, a citizen of the United States, residing at Altoona, in the county of Blair and State 5 of Pennsylvania, have invented certain new and useful Improvements in Dampers for Boilers, of which the following is a full, clear, and exact description.

The invention which constitutes the subject matter of this application relates to a means for automatically regulating the flow of furnace gases among the superheater elements whenever the flow of steam through said elements is shut off.

Referring to the drawings, Figure 1 illustrates a longitudinal section of a portion of the boiler and smokebox. Fig. 2 is a central section of the automatic damper mechanism, and Fig. 3 is a view of the damper mechanism taken on the line 3—3 of Fig. 2.

In detail the reference number 10 designates the forward portion of a locomotive or other boiler of the fire tube type suitably connected to the smoke box 11 and provided 25 with the usual tube sheet 12. The boiler is provided with a plurality of fire tubes 13 sufficiently enlarged to receive the superheater coils 14 as will be understood. The inlet ends of these elements are connected 30 to the saturated steam compartment 15 and the outlet ends to the superheated steam compartment 16 of the cylindrical or drum header 17. The steam is conducted from the boiler to the saturated steam compartment 15 by means of the pipe 18 and the superheated steam is conducted from the compartment 16 to the engine by means of the pipe 19. During the periods when the throttle is closed there is no flow of steam 35 through the superheating coils and the latter would be subjected to ruinous destruction by the intense heat passing through the enlarged tubes 13 if some means were not provided to shut off the flow of gases 40 through the latter. I am aware that this idea of shutting off the flow of furnace gases through said enlarged tubes at those periods is broadly old. My invention therefore resides in improved means for automatically 45 accomplishing this function. The flow of gases through the enlarged tubes is prevented by means of the baffles 20 and 21 and the damper 22. The baffles 20 and 21 extend substantially across the smoke box 50 as will also be understood. The damper is mounted to rotate about the axis of shaft 55

or journal 23 and when in the full line position shown in Fig. 1 it acts in conjunction with the baffles 20 and 21 and with the strips 24—see Fig. 3; only one shown—to 60 shut off the flow of gases through the enlarged fire tubes. The ends of the journal 23 is mounted to rotate in suitable bearings 25, only one being shown. The other journal for the damper is not illustrated. Upon 65 one end of shaft 23 is fixedly secured an arm 26 the outer end of which is provided with a counterweight 27. Secured to the bracket 28, upon which one of the journals 25 is secured, is a damper cylinder 29 through 70 which the arm 26 projects. This cylinder is provided with a piston 30 which reciprocates in the enlarged portion 31 of the cylinder 29 and which is connected to a slotted stem 32 which snugly fits the reduced portion 75 of the cylinder. The arm 26 also projects through the slot of the stem 32 and normally rests upon the antifriction roller 33. The lower end of the damper cylinder is connected by a pipe 34 to the valve 80 chest 35.

The operation of the device is as follows: When the throttle valve is closed, and the steam therefor shut off from the engine, the parts will be in the position shown in full 85 lines in Fig. 1. When the throttle is opened steam will be admitted through the pipe 34 to the lower side of the piston 30 forcing the same upwardly thereby oscillating the arm 26 and the shaft 23 to open the damper 90 22. As soon as the throttle valve is closed the piston will be forced to normal position by means of gravity of the counterweighted arm 26 and the damper closed. This damper will shut off the flow of furnace 95 gases through the enlarged tubes and prevent the heat from otherwise injuring the superheater elements located therein.

From the above description it will be seen that the automatic control is reduced to the 100 simplest form and to the minimum number of parts.

What I claim is:

1. The combination with a steam boiler having fire tubes and a superheater located 105 in said fire tubes, of an oscillatory damper journaled in the smoke box of said boiler and adapted to control the flow of gases through said fire tubes, mechanism operated by means of fluid pressure from the locomotive and adapted to close said damper when the flow of steam to the superheater is cut

off and to open the same when the steam is turned on, comprising a movable piston stem provided with a slot therein, and an arm fixedly secured to the oscillatory damper 5 shaft and projecting through said slot, substantially as described.

2. The combination with a steam boiler having fire tubes and a superheater located in said fire tubes, of a damper controlling 10 the flow of gases through said fire tubes and provided with a shaft about which it is adapted to be oscillated, and means for closing said damper when the flow of steam through said superheater is shut off and to 15 open the same when the flow is turned on, comprising a counter-weighted oscillatory arm fixedly secured to the said shaft, a fluid pressure mechanism provided with a reciprocating element directly and operatively 20 connected to said arm, and means for admitting fluid to and discharging the same from said fluid pressure mechanism to reciprocate said element.

3. The combination with a steam boiler 25 having fire tubes and a superheater located in said tubes, of a damper for controlling the flow of gases from said fire tubes, said damper being provided with a shaft about which it is adapted to be oscillated, and 30 means for actuating said damper adapted to close said damper when the flow of steam is cut off and to open the same when the steam is turned on, comprising a counter-weighted arm normally acting by gravity to 35 maintain said valve closed, a cylinder, a reciprocating member in said cylinder directly connected to said counter-weighted arm, and means for admitting fluid to said cylinder to actuate said member.

4. The combination with a steam boiler 40 having fire tubes and a superheater located in said fire tubes, of a damper controlling the flow of gases from said fire tubes, said damper being provided with a shaft about

which it is adapted to oscillate, means for actuating said damper, adapted to close said damper when the flow of steam to the superheater is cut off and to open the same when the steam is turned on, comprising a counter-weighted arm normally acting by gravity to maintain said valve closed, a cylinder, a reciprocating member in said cylinder, connected to said counter-weighted arm and actuated by fluid pressure to oscillate said arm against the force of gravity of said counter-weight, anti-friction means interposed between the reciprocating member, and the counter-weighted arm, and means for admitting fluid to and discharging the same from said cylinder to reciprocate the member therein and oscillate the damper.

5. The combination with a steam boiler having fire tubes and a superheater located in said fire tubes, of a damper controlling the flow of gases through said fire tubes and provided with a shaft about which it is adapted to be oscillated, and means for closing said damper when the flow of steam through said superheater is shut off and to open the same when the flow through the superheater is turned on, comprising a cylinder provided with a slot extending through the wall thereof, a piston and a piston stem movable in said cylinder, an arm fixedly secured to the said damper shaft, said arm projecting through said slot in the cylinder, and engaging with said piston stem, and means for admitting fluid to and discharging fluid from said cylinder to reciprocate said piston and stem to oscillate the damper.

In testimony whereof I affix my signature in the presence of two subscribing witnesses.

CHARLES D. YOUNG.
